UNITED STATES PATENT OFFICE.

ROBERT C. ELLRICH, OF SOUTHBURY, CONNECTICUT.

DESIGN FOR A BAR OR STOCK OF WRENCHES.

SPECIFICATION forming part of Design No. 20,448, dated January 6, 1891.

Application filed November 24, 1890. Serial No. 372,537. Term of patent 7 years.

To all whom it may concern:

Be it known that I, ROBERT C. ELLRICH, of Southbury, in the county of Hartford and State of Connecticut, have invented a new 5 Design for a Monkey-Wrench; and I do hereby declare the following, when taken in connection with accompanying drawing and the letters of reference marked thereon, to be a full, clear, and exact description of the same, 10 and which said drawing constitutes part of this specification, and represents a view in side elevation of so much of a monkey-wrench as embodies my design.

This invention relates to a design for the 15 bars or stocks of monkey-wrenches; and the design consists in the particular conformation of the respective ends of the bar or stock,

as illustrated in the drawing. The handle end A of the bar or stock is cylindrical in shape and presents a roughened surface. The 20 inner or shank end B is of cylindrical shape, smaller in diameter than the cylindrical part A, and presents a smooth surface.

I claim—

The design for the bar or stock of a monkey- 25 wrench, as herein shown and described.

In testimony whereof I have signed this specification in the presence of two subscribing witnesses.

ROBERT C. ELLRICH.

Witnesses:

JOHN M. SHARP,
JOSEPH R. DOOLITTLE.
